STRIP USED IN FORMING A SOLAR SCREEN

William C. Heirich, 515 S. 15th St.,
Muskogee, Okla. 74401

Filed Aug. 8, 1966, Ser. No. 3,390

Term of patent 14 years

(Cl. D54—2)

FIG. 1

FIG. 2

FIG. 3

FIG. 4

FIG. 5

FIGURE 1 is a perspective view of a strip used in forming a solar screen;

FIGURE 2 is a front view thereof;

FIGURE 3 is a top plan thereof;

FIGURE 4 is a front view of a strip used in forming a solar screen in sloping position; and

FIGURE 5 is a sectional view taken along line 5-5 of FIGURE 3.

I claim:

The ornamental design for a strip used in forming a solar screen as shown.
